UNITED STATES PATENT OFFICE

133,043

DESIGN FOR A GAS METER CASING

Ernest W. Powell, Galveston, Tex.

Application August 7, 1941, Serial No. 102,725

Term of patent 14 years

To all whom it may concern:

Be it known that I, Ernest W. Powell, a citizen of the United States, residing at Galveston, in the county of Galveston and State of Texas, have invented a new, original, and ornamental Design for a Gas Meter Casing, of which the following is a specification, reference being had to the accompanying drawing, forming part thereof.

Figure 1 is a front elevational view of a gas meter casing showing my new design.

Figure 2 is a rear elevational view thereof, and Figure 3 is an end elevational view thereof.

I claim:

The ornamental design for a gas meter casing, as shown.

ERNEST W. POWELL.
